Patented Apr. 10, 1928.

UNITED STATES PATENT OFFICE.

ELY PRIMEAUX, OF NEW ORLEANS, LOUISIANA.

SANDPAPERING AND BUFFING MACHINE.

Application filed May 3, 1926. Serial No. 106,441.

My present invention pertains to sandpapering and buffing machines and it contemplates the provision of a simple, inexpensive and readily portable device through the medium of which automobiles or other highly polished surfaces may be easily and quickly polished, sand papered and otherwise buffed with but a slight amount of effort on the part of the operator.

10 The invention further contemplates a portable sanding and buffing machine for the purpose set forth that is adapted for being readily interchangeable with respect to the buffing element employed.

15 The invention in all of its details will be fully understood from the following description and claim when the same are read in connection with the drawings accompanying and forming part of this specification, in which

20 Figure 1 is a side elevation of my novel device.

Figure 2 is an inverted plan view thereof.

25 Figure 3 is a sectional view of Figure 1. Figure 4 is a view taken in the plan indicated by the line 4—4 of Figure 1 and looking in the direction of the arrows.

30 Figure 5 is a side elevation of a sand papering element that may be substituted for the buffing element.

Similar numerals of reference designate corresponding parts in all the views of the drawings.

35 My novel device comprises a casing that is indicated as a whole by 1 and the said casing is provided with the curved guard portions 2 and an edge lower portion 3 and arranged in the edge portion 3 is an indented surface 4 at one end and an indented surface 5 at the opposite end of the casing, the indented portion 5 being slightly larger than the portion 4, for a purpose herein-after specified.

40 Secured to the forward portion of the casing 1 is a bearing strap 6 that is held to the casing by means of the bolts 7. This strap rests in the indented portion 4 of the edge 3 and not only depends slightly below the edge 3 but is firmly held against the casing and against side-wise movement by the abutting edges of the indented surface 4 of the edge 3. Similarly secured at the rear portion of the casing as referred to in this specification is a bearing strap 8 that is secured to the casing by means of a bolt 9 and this strap rests between the abutting edges

of the indented portion 5 of the edge portion 3 and depends from the edge 3 approximately the same length or distance as the strap 6. These straps are similar in construction except that the strap 8 is adjustable which is accomplished by providing a semicircular slot 11 and adjusting bolt 10. The purpose of this adjustment is to take up wear and the further purpose will be appreciated by reference to the later description of the device.

Secured in the bearing strap 6 is a shaft 12 and mounted on this shaft is a roller 13 while secured in the bearing strap 8 is a shaft 14 on which is arranged the spool or drum 15. The roller 13 is in fact a drum similar to the drum 15.

45 Adapted to rotate through the medium of the rotatable drums 13 and 15 is an endless belt 16 and in Figure 1 I have illustrated the belt 16 as provided with sheep wool or other high-grade buffing material 17, but at this point I would distinctly have it understood that the endless belt may be provided with any buffing material, such for instance as sand paper, emery or the like. The endless belt 17 is readily adjustable by means of the adjusting bolt and slot 10 and 11.

50 Mounted on and preferably bolted to casing 1 is a light motor 18 that is provided with a V type pulley 19 and adapted to rotate through means of the pulley 19 is a pulley belt 20 that in turn actuates a V type pulley 21 fast on the shaft 12. Apparently rotation of the pulley 19 will impart rotation to the pulley 21 which in turn rotates the drum 19 thereby imparting movement to the belt 16 and the drum 15. In this manner actuation of the buffing element is accomplished.

55 In order to assist in the easy handling of the device I have provided a handle 22 that is adjustably mounted at 23 on the casing 1.

Although I have deemed it unnecessary to illustrate nevertheless I would have it understood that the drums 13 and 15 may be removably arranged in the casing 1 and released through means of a trigger from the casing so that removal of one buffing element and replacement of another may be accomplished. Any form of construction that is well known in the art may be employed for this purpose and I make no specific claim to this arrangement.

60 It must be borne in mind that the primary and salient feature of my invention is the

distinctly novel sand papering features of the device and though I have shown the device for use as a buffing machine, I prefer that the improvements be confined to sand papering.

When desired the belt 24 having the sand paper surface 25 may be substituted for the buffing element 17.

Having described my invention, what I claim and desire to secure by Letters Patent is:—

In a buffing machine, the combination of a casing open at its lower ends and having indentations in the lip of its side walls; one of which indentations is slightly larger than the other, bearing straps secured to the side

walls of the machine; one of said straps being retained snugly in one of the indentations and the other of which is adapted to be adjusted with respect to the side wall 20 and within the complementary indentations, a slot formed in one of the straps to engage adjusting means, shafts journaled in the lower ends of the straps, drums mounted on the shafts, a buffing element arranged on an 25 endless belt; said endless belt being actuated by the drums and means for actuating one of the shafts.

In testimony whereof I have hereunto set my hand.

ELY PRIMEAUX.
